UNITED STATES PATENT OFFICE.

ALFRED M. ZIEGLER, OF BOSTON, MASSACHUSETTS.

GARMENT-SUPPORTING ATTACHMENT.

SPECIFICATION forming part of Letters Patent No. 367,492, dated August 2, 1887.

Application filed April 26, 1887. Serial No. 236,144. (No model.)

To all whom it may concern:

Be it known that I, ALFRED M. ZIEGLER, of Boston, county of Suffolk, and State of Massachusetts, have invented an Improvement in 5 Garment-Supporting Attachments, of which the following description, in connection with the accompanying drawings, is a specification, like letters on the drawings representing like parts.

10 This invention has for its object the production from wire of a durable and serviceable stocking or garment supporting attachment.

My improved supporting attachment is composed of a single wire suitably joined at its 15 ends to form the upper end of the attachment, the sides of the attachment being bent to form springs and leave a converging slot leading toward the lower end of the attachment, into which slot the fabric to be engaged and held 20 is drawn, the strain exerted by the fabric within the slot tending to straighten the spring parts of the attachment and cause the wire at the sides of the converging slot to approach each other and grasp the fabric more firmly.

25 Figure 1 in perspective shows a portion of a stocking-supporter provided with an attachment embodying my invention. Fig. 2 shows the attachment by itself, and Figs. 3 and 4 modified forms of my invention.

30 Referring to Figs. 1 and 2, the attachment made from wire has its ends overlapped and soldered or otherwise united together in usual manner, as at *a*. From its upper end the sides *b* diverge, and thereafter, or between the upper 35 end, *a*, of the attachment and point *c* and *d*, the wire is bent to constitute springs, beyond which springs, toward and to the lower end, *e*, of the attachment, the wire is so bent as to

leave a converging slot with side walls, *d d*. The strap, as *f*, to which the attachment is secured, is passed through the upper enlarged end or eye of the attachment, and is secured about the end *a* in usual manner, as by stitching.

In the modification, Fig. 3, the spring part of 45 the attachment is somewhat differently shaped; but the strain of the fabric in the diverging slot between the side walls, *d*, acts to draw the spring-sides of the attachment between the walls *d* and the end *e* toward the center of the 50 attachment, as shown by dotted lines.

In Fig 4, showing another modification of 55 my invention, the spring portions are given substantially a full instead of a half or partial turn.

I claim—

The garment supporting attachment herein described, composed of a single wire connected together at the top or upper end of the attachment, the said wire being bent, substantially 60 as described, to leave a slot having single opposed side walls, for the reception between them of the fabric to be held, the said wire between the said arms *d* and the upper end of the attachment being bent to form a spring, 65 whereby strain upon the fabric between the said side walls causes the springs to be strained to clasp or hold the fabric more firmly:

In testimony whereof I have signed my name to this specification in the presence of two sub- 70 scribing witnesses.

ALFRED M. ZIEGLER.
